UNITED STATES PATENT OFFICE.

RICHARD D. LIVINGSTON, OF CHICAGO, ILLINOIS, ASSIGNOR TO SIGNODE SYSTEM, INC.,
OF CHICAGO, ILLINOIS, A CORPORATION OF DELAWARE.

SHINGLE-STRAPPING SUPPORT.

Application filed July 15, 1921. Serial No. 484,904.

To all whom it may concern:

Be it known that I, RICHARD D. LIVINGSTON, a citizen of the United States, and resident of Chicago, in the county of Cook and State of Illinois, have invented a certain new and useful Improvement in Shingle-Strapping Supports, of which the following is a full, clear, concise, and exact description, reference being had to the accompanying drawings, forming a part of this specification.

My invention relates to improvements in means for applying bails to packages, and is particularly concerned with the provision of novel means for applying bails to packages where it is desired to apply a plurality of bands to a package, either where the bands pass around the package in the same direction, or in directions at an angle to each other.

The objects of my invention are:

First: To provide means for expediting and facilitating the application of bands to packages of all kinds.

Second: To provide means for quickly and easily applying a plurality of bands to a package where said bands are applied to the package in spaced relation, or in directions at an angle to each other.

Third: To provide novel means for supporting a package with its binding axis parallel with the axis of a coil of strap or other binding material so that the strap can be easily transferred from the coil to a position about the package.

Fourth: To provide means of the character described, whereby the package can be easily and quickly moved to bring a new part of the package into the proper relation to the coil supporting means to receive a bail.

Fifth: To provide a novel support for packages to be bound, which will provide rigid support for the package, and, at the same time, permit the package to be bound without the necessity of lifting it for the passage thereabouts of the bail.

Sixth: To provide a novel support for a package, from which the package can be easily and quickly removed after being bound.

Seventh: To provide means for supporting a package while being bound, comprising a member which is bound to the package during the binding operation, but which

is of such shape and dimensions as to permit the package to be withdrawn from it without materially affecting the tensioning of the bail, and

Eighth: To provide means which is particularly adapted for strapping objects such as shingles, panels, plaster board, and other similar objects, into bundles.

Other objects will appear as this description progresses, reference being had to the accompanying drawings, in which

Figure 1 is a side elevation, partly in cross section, of a strapping stand forming a part of my invention, which I have here illustrated as being used for forming and strapping a bundle of shingles;

Figures 2 and 3 are similar plan views showing the stand in two different positions;

Figure 4 is a transverse section taken on line 4—4 of Figure 1;

Figure 5 is a perspective view of a strapped bundle of shingles;

Figure 6 is a front elevation of a modified form of strapping stand;

Figure 7 is a vertical section taken on line 7—7 of Figure 6;

Figure 8 is a plan view;

Figure 9 is a view similar to Figure 8, but showing a completely strapped bundle in place on the strapping stand, the stand having been rotated 180°;

Figure 10 is a side elevation showing a still further modified form of strapping stand in combination with a frame or support for holding a coil of binding material with the axis thereof substantially parallel with the strapping axis of the package to be bound, and

Figure 11 is a plan view of the construction shown in Figure 10.

Referring for the present to Figures 1 to 5 inclusive, in which I have illustrated my improved strapping stand used for the purpose of applying bands to a bundle of shingles or other similar objects, I provide a table 1, upon the arm 2, pivotally mounted on bolt 3 in the stand 4. The table 1 is in the form of a rectangular oblong (for supporting a corner of the pile) from which projects a diagonal extension (for supporting the rest of the pile). The plates 5, attached to the two outer margins of the table, serve to square the edges of the pile at one corner, and the elongated thin

metal extension 6, projecting diagonally from the opposite corner completes the support for the pile. Thus, a pile of shingles 7 may be stacked on the table 1, and extension 6, and squared by the corner plates 5. Stacking is facilitated by the slight inclination of the table and corner plates as shown in Figure 1.

I shall now describe the strap guiding means. Between the edges of the extension 6 and the adjacent corners of the table are depending vertical flanges 8, which may be secured to the table by screws 9 or by other suitable means. As shown in Figs. 1 and 2, when a pile of shingles is on the table, the plates 8 will each lie approximately at the center of the pile. A tensional binder 10 can then very quickly be applied about the center of the pile of shingles, which is entirely exposed except for the thin plate 6 around which the binder is put, as shown in Fig. 1. The flanges 8 serve as an accurate guide for the strap. In other words, the strap, while being wrapped about the pile, is pushed sideways up against the one or other of the flanges 8, which insures its proper position at the center of the pile, after which it is tightened and a joint 11 formed in the ordinary way.

For convenience in operation, I have mounted the table 1 pivotally upon the standard 4 and have provided the bolt 12, working in the quadrant recess 13 in the head 14 of the stand 4. By this means the table 1 may be revolved ninety degrees so as to bring the pile with its long or short side respectively directly in front of an operator and to permit the application of the two binders with equal facility in a manner clearly illustrated in Figs. 2 and 3. It will be observed that the arm 2 which supports the table, extends, not only upwardly, to afford a clearance over the top of the stand, but also outwardly. This offsets the table so that either of its two inner edges is aligned with the axis of revolution, and the strapping operation is carried out in the same plane, for both straps, the table being turned ninety degrees as described.

For further convenience I have mounted the standard 4 within the standard 15, secured upon a base 16, and have provided the holes 17 through which projects the pin 18, projecting also through aligned apertures in the standard 15. By this means, the table 1 may be adjusted in height. A set screw 19 prevents play of the standard 4 in the standard 15.

In operation, the pile of shingles is quickly placed upon the table 1 and "squared up" against the corner plates 5. After this with the table 1 in the position shown in Fig. 2, a binder 10 is applied, the flange 8 serving as a guide; immediately the table 1 is revolved ninety degrees bringing the parts in

the position Fig. 3, whereupon the other strap 10 is applied in the same way. The completed bundle is pulled outwardly along and off the thin extension 6, the whole operation being performed in a very few seconds. It will be observed that the table 1 is within an area of the bundle not covered by strap, and is of heavy construction, and will stand hard usage, as well as provide a firm support for the package. While the extension 6 is included with the bundle in the strapping operation, it is light and thin. As a result of the above construction, my improved strapping stand affords a firm support for the package without in any way detrimentally affecting the tension of the bands or binders, by reason of the inclusion of the extension 6 with the bundle during the binding operation.

In Figs. 6 to 9 inclusive, I have illustrated a modified form of my strapping stand in which I provide a table 21, preferably formed of wood, the upper surface of which is covered with a heavy sheet metal plate 22, the rear portion of which is bent upwardly at a right angle to the table 21 to provide a back plate 23, and one end of which projects from the end of the table 21 to provide an extension 24 for supporting one end of the package to be bound. For the purpose of strengthening the extension 24 against bending stresses, I prefer to provide the plate 22 with a longitudinally extending corrugation 25. This corrugation tapers in depth from a maximum depth at a point adjacent the table 21 to practically nothing at the outer end of the extension. The maximum depth of the corrugation should not be sufficient to materially affect the tension of the band or binder when the package is removed from the stand. A guide bar 26 extends downwardly from each side of each end of the table 21 to provide means for guiding the strap or other binding material into the proper position on the package.

For the purpose of rotatably supporting the table 21 and the parts attached thereto, I provide a stand comprising a base 27 which supports a standard 28, the upper end of which is secured to the head 29. A plate 30 is rotatably mounted upon the head 29 and is pivotally held thereon by means of the bolt 31 which extends upwardly through the head 29 and a suitable opening in the plate 30. Nuts 32 at the upper end of the bolt 31 prevent the table from being lifted from the stand. The plate 30 is provided with a plurality of upwardly extending bosses 33 to which the table and its sheet metal cover 22 are secured by means of the screws 34. At 35 and 36 I have illustrated a discontinuous duct passing through the table 21 and the plate 30 for conducting lubricant to the upper surface of the head 29.

- In using the strapping stand described above, the box, package, or stack of material to be bound is placed upon the stand in the position indicated in dotted outline in Figure 8. A strap 37 is then placed around the package at substantially its middle point. This strap will, of course, include the extension 24 with the package. Another strap 38 is then placed around the package adjacent to the end of the extension 24, or, if necessary, placed around the bundle to include this extension. The table 21 is then rotated 180° upon its axis, and the strap 39 applied to the other end of the package or bundle. The package can then be withdrawn from the stand in a left hand direction (Fig. 9). Similar to the extension 6 shown in Figs. 1 to 4 inclusive, the extension 24 shown in Figs. 6 to 9 inclusive is in such shape and such dimension that its inclusion in a package does not materially affect the tension of the band or binder when the package is removed from the strapping stand.
- It will be noted that in the modified form of my invention shown in Figs. 6 to 9 inclusive, the pivotal support is not at the longitudinal center of the table 21, but is located relatively near one end of this table, this being for the purpose of bringing the pivotal support at substantially the center of the package to be bound.
- In Figs. 10 and 11, I have illustrated my complete invention in which the strapping stand forming a part thereof is similar to that shown in Figs. 6 to 9 inclusive, except that the extension 24 shown in the last mentioned figures is omitted, and the pivotal support for the table 21 is positioned substantially centrally of the table. In Figs. 10 and 11, I have shown in combination with the strapping stand a frame for supporting a coil 40 of strap, or other suitable binding material, in a substantially vertical position, this frame comprising the two side members 41, cross member 42, to which are secured the backing bars 43. Two braces 44 prevent the supporting frame from tipping over. An arm 45 is secured to the backing bars 43 in such manner that it projects outwardly through the coil. The outer end of the arm 45 is provided with a clip 46 for holding the free end of the strap when it is not being manipulated about a package. If desired, the coil supporting frame and the strapping stand may be secured to the same platform 47.
- In the use of the apparatus illustrated in Figs. 10 and 11, a plurality of convulsions 48 can be transferred from the coil 40 to the arm 45, where they will be within easy reaching distance of the operator. The operator can then, by a single movement, transfer a convolution of the coil 40 to a position about one end of the package.
- The overlapping positions of the strap can then be secured by a suitable seal 50, and the free portion of the strap broken or otherwise severed from the band and secured under the clip 46. The support and package is then rotated to bring the opposite end of the package into the proper position relative to the coil 40 to receive another convolution or portion of a convolution of the coil 40 and the operation of securing the strap to the package repeated.
- While I have described the coil supporting frame only in connection with the strapping stand illustrated in Figs. 10 and 11, it is to be clearly understood that it can be similarly used in connection with the strapping stands illustrated in the remaining figures of the drawings, and that I have not illustrated such use merely for the purpose of saving illustration. The strapping stands which I have illustrated can, however, be used to good advantage without a coil supporting stand.
- While I have described the details of construction of the preferred embodiment of my invention, it is to be clearly understood that my invention is not limited to these details of construction, but is capable of other adaptations and modifications within the scope of the appended claims.
- Having thus described my invention, what I claim is:
1. In apparatus of the class described, a support for a bundle of shingles or the like including a shoulder located under said bundle when the same is placed on the support, said shoulder forming a guide for a binder applying operation, and serving to locate the binder.
  2. In apparatus of the class described, a rack adapted to hold a pile of shingles, a shoulder on said rack adapted to form a binder guide and an extension from the rack extending beyond the shoulder and adapted to assist in supporting said pile.
  3. In apparatus of the class described, a rack having vertical sides adapted to re-cede and "square up" a pile of shingles, or the like, and including a support for the bottom of said pile, and a shoulder on said support adapted to form a guide for positioning a binder.
  4. In apparatus of the class described, a rack having vertical sides adapted to receive and "square up" a pile of shingles, or the like, and including a support for the bottom of said pile and a shoulder on said support to form a guide for positioning a binder, said shoulder being located approximately centrally of the pile.
  5. A support for a pile of shingles or the like, while being strapped, comprising a vertical corner piece, a table for one corner of the pile, shoulders on said table to form strap guides, and an extension from said

table extending beyond said shoulders to support the remainder of the pile.

6. A support for a pile of shingles or the like, while being strapped, comprising a vertical corner piece, a table for one corner of the pile, shoulders on said table to form strap guides, and an extension from said table to support the remainder of the pile, said table being pivotally mounted and adapted to be turned on a vertical axis.

7. In apparatus of the class described, a table having corner pieces and adapted to underlie and support one corner of a pile of shingles, a thin extension from said table toward the opposite corner of said pile.

8. In apparatus of the class described, a table having corner pieces and adapted to underlie and support one corner of a pile of shingles, a thin extension from said table toward the opposite corner of said pile, and means whereby said table may be revolved through an arc of ninety degrees.

9. In apparatus of the class described, a table adapted to underlie and support one corner of a pile of shingles, a thin extension from said table toward the opposite corner of said pile, means for adjusting the height of said table, and means whereby said table may be revolved about a horizontal axis.

10. In apparatus of the class described, a revolvable table for strapping shingles or the like, having the shape and area of substantially one quarter of the under surface of the pile being supported, and a thin extension adapted to support the remainder of the pile.

11. In apparatus of the class described, the combination of a support, a table rotatably mounted on said support for motion into different positions relative to a predetermined plane in which a binder is applied around the bundle supported on said table, said table having two right angle edges parallel with and in close proximity to the longitudinal and transverse median planes of the bundle, said edges being rotatable into substantial parallelism with said binding plane, and stop means for confining one of the edges of the bundle to one of the other edges of said table.

12. In apparatus of the class described, a standard, an arm extending upwardly and outwardly from the standard, and a table extending inwardly and horizontally from the outer end of said arm.

13. A table for strapping shingles or the like, comprising a substantial strain resisting portion, adapted to underlie a portion of the bottom of a bundle of shingles or the like free from binders, a thin extension from said table adapted to underlie an additional portion of said bundle to complete a support for the same, said extension being adapted to be included with the bundle in the strapping operation and to be withdrawn slidably from the embrace of the binder after the strapping operation.

14. A table for strapping shingles or the like, comprising a substantial strain resisting portion, adapted to underlie a portion of the bottom of a bundle of shingles or the like free from binders, a thin extension from said table adapted to underlie an additional portion of said bundle to complete a support for the same, said extension being adapted to be included with the bundle in the strapping operation and to be withdrawn slidably from the embrace of the binder after the strapping operation, said table being revolvably mounted.

15. The combination with a support for holding a coil of binding material in a substantially vertical position, of a rotatable support adjacent said first named support for holding a package in any one of a plurality of different positions with its binding axis substantially parallel with the axis of said coil.

16. The combination with an adjustable support for holding a package with any one of its binding axes in a given position, of a support for holding a coil of binding material so that its plane will be substantially parallel with any of said axes when in said given position.

In witness whereof, I hereunto subscribe my name this 8th day of July, 1921.

RICHARD D. LIVINGSTON.
